UNITED STATES PATENT OFFICE.

RICHARD H. WELLES, OF KENOSHA, WISCONSIN, ASSIGNOR TO THE BADGER BRASS MFG. CO., OF KENOSHA, WISCONSIN, A CORPORATION OF WISCONSIN.

LAMP.

1,170,378.

Specification of Letters Patent.

Patented Feb. 1, 1916.

Application filed April 30, 1914. Serial No. 835,356.

To all whom it may concern:

Be it known that I, RICHARD H. WELLES, a citizen of the United States, residing at Kenosha, in the county of Kenosha and State of Wisconsin, have invented certain new and useful Improvements in Lamps, of which the following is a specification.

My invention relates to improvements in lamps, and refers more particularly to electric head lamps used on automobiles and for other outdoor purposes.

The salient objects of the invention are, to provide a construction in which the reflecting surface is maintained at all times clean and bright by providing a gas-tight seal which prevents the access of impure air or vapors to the polished surface of the reflector; to provide a construction of the class described in which the glazing of the lamp may be readily removed with a minimum amount of manipulation while at the same time securing a sealed gas-tight joint when the lamp is closed; to provide a construction of the class described in which the lamp door carrying the glazing is resiliently clamped against the end of the lamp body, thus taking care of mechanical inaccuracies in constructing the various parts of the lamp; to provide a construction in which a single movement of the lamp door both seals the casing and securely locks the door to the front of the lamp; to provide a construction in which a rotary movement of the lamp door results in a gradual increase in pressure upon the gas-tight seal as the door advances into its closed position; to provide a construction in which resilient locking means are employed to prevent the accidental loosening up of the door and consequent leakage of the gas-tight seal; to provide a construction which will be simple and economical in construction, and, in general, to provide an improved lamp of the character specified.

My invention consists in matters herein-after described and more particularly pointed out in connection with the accompanying drawings, in which—

Figure 1 is a front elevation of a head lamp embodying my construction; Fig. 2 is a side elevation of Fig. 1; Fig. 3 is a front elevation of the lamp shown in Fig. 1, the glazing door being removed; Fig. 4 is an elevation of the door removed from the lamp

shown in Fig. 1 and looking through the glazing from the inside; Fig. 5 is a fragmentary section taken along the line 5—5 of Fig. 1; Fig. 6 is a view similar to Fig. 5 but taken at a different point in the circumference of the lamp so as to show the locking means; Fig. 7 is a partial fragmentary section taken along the lines 7—7 of Figs. 3 and 6; Fig. 8 is a fragmentary elevation of a portion of Fig. 1 showing certain parts broken away in order to bring out the mechanical construction of the locking devices; Fig. 9 is a section taken along the line 9—9 of Fig. 8, and Fig. 10 is a section through the locking button taken along the line 10—10 of Fig. 8.

In a preferred embodiment of my construction, illustrated in the drawings, the lamp shown is an automobile head lamp comprising an outer casing 1, an inner reflector 2, the front end of which is inclosed by a glazing 3 supported in an annular removable door or frame 4. The electric lamp 5 is seated in the focus of the reflector and is supplied by current through an electric connector 6. Upon the outer casing 1 is formed an inwardly projecting annular flange 7 upon which is clamped an outwardly projecting flange 8 formed integral with the reflector portion 2, and between these two flanges is interposed a sealing gasket 9 which is thus clamped between the two flanges by a plurality of bolts distributed along the circumference. These bolts comprise fillister head screws 10 which are threaded into nuts 11 soldered to the under side of the inwardly projecting flange 7. The removable door 4 consists of a ring the cross-section of which forms part of a circle, and brazed or soldered to this ring is an annular partition member 12. The inner portion of the circular ring 4 projects beyond the inner cylindrical portion 12^a of the member 12, and there is thus formed an annular pocket, triangular in cross-section, in which is seated the gasket 13. This gasket 13 may be a rope of cotton or other suitable material of a sufficient diameter to form a seal and cushion for the glazing 3 which is clamped against it by means of a plurality of inwardly projecting clamps 14, these clamps being screwed to the member 12 by means of a plurality of fillister head screws 15 which are threaded into nuts 16 soldered

to the inside of the member 12. The member 12 is suitably die-formed so as to provide an inwardly turned flange 17 which is of the proper diameter to engage the edge of the gasket 9, previously referred to.

I will now describe the means for resiliently clamping the door to the body of the lamp. Distributed around the circumference of the door and body are a plurality of 10 clamping devices, in this case four, each of which comprises a cam hook 18 which is riveted and soldered to the cylindrical portion 12^a of the part 12 of the door, and projects through slots 19 punched in the flanges of the reflector and of the outer casing. The 15 cam hooks 18 are constructed of comparatively heavy metal and are notched out at their inner ends to form cam surfaces 20 suitably located to engage the plate springs 21. The plate springs 21 are also slotted out 20 in order to admit the ends of the locking hooks and are riveted and soldered at one of their ends to the under side of the flange 9 of the outer casing, the other end of the 25 spring being left free so as to furnish the required resiliency.

In order to clamp the door to the casing, the hooks are inserted into the slots by an 30 axial inward movement of the door, and then, after the door has become properly seated in the body, the door is given a slight 35 rotary movement in the direction of the arrow 22, shown in Fig. 7. At the commencement of this rotary movement the point 23 of each of the hooks slides below the end 24 of the slot in the free end of the spring which thus moves axially outward as the hook is 40 rotated, and so resiliently presses the door and casing together. It will be noticed that the clamping together of the door and the 45 casing compresses the gasket 9 between the flange 7 and the annular flange 17 on the inner face of the door and thus seals the lamp against the admission of impure air or noxious vapors.

In order to prevent the loosening up of the door, due to the vibration of the car, I employ a subsidiary locking device. This 50 comprises a spring-pressed plunger 25 which is so placed in the circumference of the door that it will occupy a position behind the filister head of one of the screws 10 and thus prevent a backward rotary movement of the door. The plunger 25 is mounted to slide in 55 a tubular sleeve 26 radially seated in the annular door, and the outer end of the plunger 27 is reduced in diameter so as to give room for the coil compression spring 28 interposed between the outer closed end of the tubular 60 sleeve 26 and the shoulder of the plunger. The reduced portion 27 of the plunger extends outwardly through the bushing 29 at the outer end of the sleeve 26, and is furnished with an ornamental head 30 screwed 65 and riveted thereto. The inner end of the

head 30 is slotted out across its diameter so as to admit an outwardly projecting rectangular portion 31 formed on the end of the building 29 by milling off its two sides.

The operation of the locking device is 70 obvious. In the position shown, the lamp is locked against rotary movement of the door. If the lamp is to be opened, the plunger is withdrawn outwardly a sufficient distance until the inner face of the button 75 30 passes beyond the end of the portion 31, and then the button is given a slight rotary movement to retain the plunger in unlocked position. The end of the plunger is thus drawn out of range of the head of the nut 80 10 and the door can be rotated and removed.

It is understood that my construction is capable of such modifications as would be apparent to a mechanic skilled in the art, without departing from the spirit of the invention, and, therefore, I do not wish to be limited to the details described except as 85 specified in the appended claims.

I claim--

1. In a lamp, the combination of a substantially bowl-shaped casing, a parabolic reflector nested within said casing, said reflector and casing being provided with an annular member connecting them rigidly together, a door provided with a glazing closing the front end of the lamp body, a gasket interposed between said door and said annular connection, and means for forcing said door toward said annular connection. 90

2. In a lamp, the combination of an outer shell provided with an inwardly projecting flange, an inner reflector shell provided with an outwardly projecting flange lapping the flange on the outer shell, an annular gasket supported in contact with the outer 100 face of one of said flanges, an annular glazing door having a glazing for closing the front end of the reflector and provided with an annular surface adapted to engage the outer annular surface of said gasket, and resilient means for clamping said door to the lamp. 105

3. In a lamp, the combination of an outer shell provided with an inwardly projecting flange, an inner reflector shell provided with 115 an outwardly projecting flange overlapping the flange on the outer shell, an annular gasket interposed between said flanges and extending beyond said inner flange, an annular glazing door having a glazing for 120 closing the front end of the reflector and provided with a flange adapted to engage the projecting surface of said gasket, and resilient means for clamping said door to the lamp. 125

4. In a lamp, the combination of an outer shell provided with an inwardly projecting flange, an inner reflector shell provided with an outwardly projecting flange overlapping 130 the flange on the outer shell, an annular

gasket interposed between said flanges and projecting from between said flanges, an annular door having a glazing for closing the front end of the reflector and provided with 5 an annular seat adapted to engage the projecting surface of said gasket, and means for pressing the door against said gasket.

5. In a lamp, the combination of an outer shell, a parabolic reflector nested within said 10 outer shell and provided with an outwardly extending flange connecting it to said outer shell, said flange being provided with a circumferentially extending slot, a spring on the inside of said flange, and a hook carried 15 by the door adapted to enter said slot and engage said spring and provided with a circumferentially sloping cam surface

adapted to compress said spring by a rotary movement of said door.

6. In a lamp, the combination of a body 20 portion having an annular gasket-seat, a door having an annular seat adapted to compress a gasket between said door and body, said door being adapted to clamp into engagement with said body by a circumferential movement thereof, and a spring-pressed plunger carried by one of said members and adapted to engage a projection on the other of said members.

RICHARD H. WELLES.
